Walter J. Barron

by Jacob Zabel

HIS ATTORNEY.

UNITED STATES PATENT OFFICE.

WALTER J. BARRON, OF NEW YORK, N. Y., ASSIGNOR TO THE DENSMORE TYPEWRITER COMPANY, OF SYRACUSE, NEW YORK.

TYPE-WRITING MACHINE.

SPECIFICATION forming part of Letters Patent No. 660,089, dated October 23, 1900.

Application filed April 4, 1898. Serial No. 676,374. (No model.)

To all whom it may concern:

Be it known that I, WALTER J. BARRON, a citizen of the United States, and a resident of the city of New York, borough of Brooklyn, county of Kings, and State of New York, have invented certain new and useful Improvements in Type-Writing Machines, of which the following is a specification.

The principal object of this invention is to so construct the cylindrical platen of the type-writing machine as that it may be used either with or without a card-holder, especially made with reference to the construction of the platen, so as to be attached to and detached from said platen; and to this main end my invention consists in the various features of construction and combinations of devices hereinafter more fully described, and particularly pointed out in the appended claims.

10 In the accompanying drawings, Figure 1 is a longitudinal central vertical section of a platen embodying my improvements. Fig. 2 is a cross-section thereof, taken at the line xx of Fig. 1. Fig. 3 is a perspective view of a 15 portion of the spring. Fig. 4 is a similar view of the card-holder or clamping-bar, and Fig. 5 is an elevation of one of the spring-pressed hooks or catches for the card-holder.

20 In the several views the same part will be 20 found designated by the same numeral of reference.

11 designate the end bars of a platen frame or carrier, which support the ends of the platen shaft or axle 2, the extremities of which are 35 preferably provided with knobs or wheels 3, each knob or wheel having a hollow shank, which is attached to the axle by means of a radial set-screw 4. The said platen shaft or axle passes centrally through the hollow core 40 5 of the platen and through the heads 6 and 7, screwed or otherwise attached to the ends thereof, and said shaft is attached to the hubs of the heads by means of a set-screw 8, all in the usual manner. The head 7 is shown as 45 provided with ratchet-teeth 9 for the customary line-spacing pawl. The platen-core is provided, as usual, with a rubber sheath or cover 10, which, near each end, is perforated radially, as is also the core, for the passage 50 therethrough of a bolt or catch device 11,

whose inner end terminates within the bore of the interior support or core 5.

The bolt or catch device 11 is threaded at its inner end and at its outer end is provided with a head 12 and a collar 13 therebelow, 55 leaving an intervening neck 14. The hole in the sheath or cover 10 is counterbored or shouldered to act as a stop for the bolt when the card-holder is detached and the platen is to be used for ordinary purposes. 60

15 designates a bar-spring, which is curved between its ends and at each end is formed or provided with a slot or fork 16 to embrace the inner end of the bolt 11. The spring is held in place upon said bolt by means of a 65 nut 17. In practice the bolts and spring and nuts are applied before the platen-heads and platen-axle are placed in position. The bolts are first passed through the cover and the core and the spring is then inserted endwise 70 in the latter to about the position shown at Fig. 1, at which time, however, the ends of the spring, owing to the natural shape and tension of the spring, stand nearer the center of the platen. One end of the spring is 75 then bent upwardly or outwardly radially of the platen, so that its fork embraces the inner end of the pin, and while the spring is held upon the pin the nut 17 is applied to confine it in place. The other end of the 80 spring is then put upon the other bolt and similarly held in position. At the conclusion of this operation the bolts are held downwardly or inwardly under the tension of the arms of the spring, with the collars 13 seated 85 against the shoulders of the holes in the platen-cover.

The card-holder or clamping-bar is designated by the numeral 18 and in cross-section may be curved to match the curvature of the 90 platen. This bar extends for practically the full length of the platen and at its right-hand end is slotted or bifurcated at 19 to embrace the neck of the right-hand bolt under its head 12, and the said bar at its left-hand end is 95 formed with a keyhole-slot 20 to engage with the neck and head of the left-hand bolt.

The bar or card-holder 18 is attached to the platen by first laying it upon the surface of the platen with the circular portion of the 100

keyhole-slot in register with the head of the left-hand bolt, which it passes over, and then by sliding the bar lengthwise of the platen toward the right, so that the parallel sides of 5 the keyhole-slot come under the head of the left-hand bolt and so that the shorter parallel sides of the slot or fork at the right-hand end of the bar also pass under the head of the right-hand bolt, whereby the bar is locked 10 in position against sidewise or circumferential movement. The said bar is at the same time held upon the surface of the platen with sufficient friction to prevent any accidental endwise movement thereof. This friction 15 may be obtained by very slightly bending the bar back out of its general plane or it may be obtained by slightly beveling the corners 21 of the slots, so that when the bar is slid endwise these corners, acting upon the under 20 side of the head, will serve to very slightly lift or draw outwardly the bolts 11 against the tension of their spring-arms, and thus cause the heads of the screws to bear harder upon the parallel edges of the slots when the 25 bar is pushed over into full engagement or to the position shown at Fig. 1. The bar is formed or provided with an extension 22 beyond the left-hand end of the platen, so as to provide a finger-piece whereby the bar 30 may be lifted from the surface of the platen for the major portion of its length and for the purpose of enabling the card to be printed to be properly introduced. When the card has been inserted, it may be adjusted to any desired 35 place on the platen, and when the finger-piece is released the spring will return the bar and cause it to properly hold or grip the card on the platen and carry it around therewith as the platen is rotated in line-space direction. Of course, if desired, each bolt may 40 be provided with a surrounding coiled spring in lieu of the flat spring shown and described and other changes in detail construction may be made without departing from the spirit of my invention. 45

When it may be desired to print upon paper in the usual manner, the card-holder may be quickly removed by sliding it endwise toward the left until the eye of the keyhole-slot 50 again registers with the head of the bolt at the left.

Although I prefer to have both bolts slide and provide a spring or spring-arm for each, nevertheless an acceptable construction may 55 be made in which the right-hand bolt or a bolt at one end of the bar is fixed in the platen and the left-hand bolt or the bolt at the opposite end is spring-pressed and movable, as described.

60 What I claim as new, and desire to secure by Letters Patent, is—

1. In a type-writing machine, the combination of a platen having two catches, one of which at least is mounted to slide radially and is provided with a spring, and an end- 65 wise-slidable card-holder constructed to be engaged with and disengaged from said catches and provided with a lifting finger-piece.

2. In a type-writing machine, the combination of a platen having at each end a spring-pressed catch, and a slotted card-holder adapted to be engaged with and disengaged from said catches by endwise movements. 70

3. In a type-writing machine, the combination of a platen having at each end a spring-pressed headed bolt, and a card-holder having longitudinal slots to engage with said bolts. 75

4. In a type-writing machine, the combination of a platen having at each end a radial perforation, a bolt extending therethrough to the inside of the platen, a spring tending to pull said bolt inwardly, and a card-holder having slots to engage with the heads of said 85 bolts.

5. In a type-writing machine, the combination of a platen provided with a hollow core and a sheath or cover, a radial hole at each end of said platen, a shoulder or seat at each hole, a bolt extending through said hole and formed with a collar and a head and an intervening neck, a spring for said bolt, and a card-holder constructed to be engaged by the heads of said bolts. 90

6. In a type-writing machine, the combination of platen, a radially-arranged bolt at each end thereof, a spring for said bolt, and a card-holder having longitudinal slots for engagement by said bolts and also having a 100 finger-piece.

7. In a type-writing machine, the combination of a platen having a radially-arranged bolt at each end comprising a head, a collar and an intervening neck, the bar-spring 15 105 forked at each end for embracing the inner ends of said bolts, nuts for holding said spring in place, and a card-holder having longitudinal slots and a finger-piece.

8. In a type-writing machine, the combination of a platen having a headed catch at each end and a card-holder slotted at each end to enable the card-holder to be attached to and detached from the platen. 110

Signed at the borough of Manhattan, in the 115 city, county, and State of New York, this 2d day of April, A. D. 1898.

WALTER J. BARRON.
